UNITED STATES PATENT OFFICE.

KARL E. BRUTON, OF WHITNEY, TEXAS.

DESIGN FOR A COOLER.

47,022.

Specification for Design.

Patented Mar. 2, 1915.

Application filed September 16, 1914. Serial No. 862,108. Term of patent 14 years.

To all whom it may concern:

Be it known that I, KARL E. BRUTON, a citizen of the United States, residing at Whitney, in the county of Hill and State of Texas, have invented a new, original, and ornamental Design for Coolers, of which the following is a specification, reference being had to the accompanying drawing, forming a part thereof.

The figure is a perspective view of a cooler, showing my new design.

I claim:

The ornamental design for a cooler, as shown.

K. E. BRUTON.

Witnesses:

H. L. ROWLAND,
A. J. HICKS.
